PISTON CONSTRUCTION

Herman Garvin, Indianapolis, Ind.

Application September 11, 1935, Serial No. 40,163

3 Claims. (Cl. 309—12)

This invention relates to piston construction, the primary object of the invention being to provide a piston having an adjustable skirt, and means for expanding the skirt into engagement with the cylinder wall in which the piston operates, thereby compensating for wear directed to the piston, and insuring a noiseless piston at all times.

Another object of the invention is to provide an expansible piston which may be expanded to accurately fit within its cylinder wall, thereby insuring the efficiency of the piston, and eliminating the necessity of replacing worn pistons.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

Referring to the drawing—

Figure 1 is a longitudinal sectional view through a piston constructed in accordance with the invention.

Figure 2 is a sectional view taken on line 2—2 of Figure 1.

Figure 3 is a bottom plan view of the piston, the bolts at one side of the piston being shown in section.

Figure 4 is a sectional view taken on line 4—4 of Figure 1.

Figure 5 is a sectional view taken on line 5—5 of Figure 3.

Referring to the drawing in detail, the reference character 5 designates the head of a piston, which is formed with extensions 6 to which bars 7 are secured, the bars 7 being curved to conform to the curvature of the inner surface of the piston.

The reference character 8 designates a sectional piston skirt, each section of the skirt being provided with a curved plate 9 formed with elongated openings 10, through which the securing bolts 11 extend, the securing bolts operating in these openings, to permit the skirt sections to be expanded to compensate for wear. Nuts 12 are mounted on the ends of the securing bolts and secure the skirt sections in their positions of adjustment.

Plates 13 cooperate with the curved plates 9

in holding the skirt sections in their positions of adjustment.

As clearly shown by Figure 3 of the drawing, bolts 14 are provided, which bolts are formed with transversely disposed pins 15 that engage the adjacent ends of the curved plates 9, when the bolts are rotated, thereby moving the adjacent ends of the plates 9 away from each other with the result that the skirt sections are expanded.

After the bolts have been operated to move the plates as described, the nuts 16 carried by the bolts 14, are tightened, thereby securing the skirt sections in their positions of adjustment.

From the foregoing it will be obvious that when the skirt of the piston becomes worn to cause the piston to rock within its cylinder, the skirt of the piston may be expanded and moved into close engagement with the cylinder wall thereby compensating for wear and insuring a close fit between the cylinder and piston eliminating what is commonly known as piston slap.

Having thus described the invention, what is claimed is:

1. A piston comprising a body portion, a sectional expansible skirt forming a part of the body portion, a curved plate secured to each skirt section, a bolt disposed between the adjacent ends of the plate, pins on the bolts and adapted to engage the ends of the plates whereby the sections of the skirt are moved outwardly, and means securing the skirt sections in their positions of adjustment.

2. A piston comprising a head, expansible skirt sections mounted on the head, curved plates carried by the skirt sections, bolts disposed between the adjacent ends of the plates, adjusting means on the bolts and engaging the adjacent ends of the plates for moving the adjacent ends of the plates away from each other, expanding the skirt sections, and means securing the skirt sections in their positions of adjustment.

3. A piston comprising a body portion, a sectional expansible skirt forming a part of the body portion, plates formed integral with the skirt sections and extending outwardly therefrom, bolts securing the skirt to the body portion, adjusting bolts, and means on the adjusting bolts for moving the plates expanding the sleeve, when the adjusting bolts are rotated.

HERMAN GARVIN.
